APPARATUS FOR TREATING GASEOUS MEDIA

Charles G. Smith, Medford, Mass., assignor to
Raytheon Manufacturing Company, Newton,
Mass., a corporation of Delaware

Application November 17, 1943, Serial No. 510,846

4 Claims. (Cl. 343—100)

1

This invention relates to apparatus for treating gaseous media with focussed radio waves.

One of the objects of the present invention is to produce a gaseous discharge in a gaseous medium by subjecting the gaseous medium to the action of focussed short wave energy.

Another object of the present invention is to subject matter to the action of focussed short wave energy and to collect its resultant products.

Another object of the invention is to provide apparatus for delivering short wave energy from a region of relatively high electrical insulation, and focussing the energy thus delivered in a region of poorer insulating quality, said two regions being independent.

These and such further aims and objects as may hereinafter appear will be readily understood from the following description, taken in connection with the accompanying drawing of one embodiment of the present invention herein given for illustrative purposes.

If short wave energy be sufficiently strongly focussed within a gaseous medium, the electrical stresses in the region of the focus can be made sufficiently intense to cause a breakdown of said gaseous medium. Energy can then be delivered to the electronic medium in the ionized region.

Referring to the drawing, the illustrative embodiment of the invention therein illustrated comprises two ellipsoidal mirrors 2 and 4, which face each other and are preferably coaxial. They are mounted upon standards 6 and 8, respectively, which may in turn be mounted upon a base 10, in manner hereinafter more fully described. Each mirror is closed in front by glass or some other suitable material pervious to short wave radiation and has associated therewith a source of short wave energy, herein conveniently consisting of an oscillator 12 which may be of any suitable and conventional construction. Means are herein provided to deliver the short wave energy from said oscillator 12 to the confined space 16 between the front and rear walls of their respective mirrors. Herein said means conveniently comprises a tubular wave guide 14 leading from the oscillator and terminating within said confined space 16 substantially at the focus of the mirror. Said wave guide 14 is preferably of the concentric conductor transmission line type having a rod 18 extending axially thereof and terminating in a radiating dipole antenna 13 for radiation at the focus of said mirror. Said rod 18 is spaced from the inner wall of said wave guide 14 by partitions 20, one of which also serves to close off the space 16, which contains any suitable insulating gas to increase the insulation of said space and prevent breakdown at the said radiating antenna 13. The same result might be obtained by using a vacuum or high pressure.

The oscillations delivered at the focus within

2

said confined space 16 of relatively high electric insulation will be reflected by mirrors 2 and 4 and will converge at their other focus f with the gaseous medium to be broken down, at which will be a region of poorer insulating quality.

The focus being situated in a localized region unlimited by boundary walls, insulators, metal containers or other hampering influences, the intense, concentrated energy will cause a free flame to be formed at the focus, which in addition to its use as a means for treating matter is adapted to other useful purposes, such as display purposes, effecting chemical reactions, etc.

The gas to be broken down may be atmospheric air or any other gas. In the case of atmospheric air the reaction can be effected in the open air and the resulting products collected in a reservoir (not shown) through a pipe 24, for example. In the case of other gases the gas may be conveniently supplied to the focal region from a suitable source of supply (not shown) through suitable feed pipe 22, and the broken down gas or other resulting products collected and conveyed through said pipe 24, for example, to a suitable collector reservoir (not shown).

Mirrors curved substantially in the arc of a circle may be suitably mounted as shown at 21, to reflect back upon the mirrors 2 and 4 respectively, any rays that may have escaped reflection by said mirrors 2 and 4, and thus cause said rays to converge at f with the others.

While focusing the energy from a plurality of sources at a common focus may increase the intensity of energy concentration at that point regardless of the vectorial relationship of the electrical vectors at said common focus, I prefer to arrange the relative positions of the radiators as the relative phase of the waves radiated therefrom so that at the common focus the electric vectors of each radiated wave are all in the same direction so that said vectors are added so as substantially to multiply the stress at the focus by the number of radiating sources. This increases the electrical stress at the focus facilitates the transfer of energy to the medium at said focus.

In some cases the reaction can be increased to a state of thermodynamic equilibrium be prevented. In order to prevent approach to thermodynamic equilibrium in the gaseous medium to be treated, the position of the focal region f may be moved and shifted about within said medium during the operation. In the illustrative embodiment of the invention herein presented, means are provided to impart a relatively rapid reciprocating angular movement to mirrors 2 and 4 about the vertical axes of standards 6 and 8. This will cause the focal region f to swing back and forth rapidly in a horizontal plane with the gaseous medium. To this end standards 6 and 8 are mounted for rocking movement about

axes in bearings 28 and 30, and a crank at the end of shaft 34 of motor 35 is connected link 33 and universal joint 36 to one end of sh. rod 38, mounted for sliding movement in sets 40, and suitably connected to cranks 42 standards 6 and 8. Operation of motor 35 will utilize the reciprocating horizontal movement referred to of said focal region *f*.

ough the focus as described above has considered as a point in space, in a practical a focal region of substantial volume is created. In using a plurality of radiating sources, resultant of the plurality of radiated waves standing wave in space whose greatest amplification occurs in the focal region. The position of top of the standing wave within the focal region will be shifted in accordance with a relative phase shift between the component waves. affords a convenient means for producing the desired shifting of the region of maximum.

To this end a phase shifting device may be provided at 44 for each oscillator 12. These devices are carried by the standards 6 and 8, respectively, and may be of any suitable conventional construction in which the phase is continually shifted by some suitable means, such as actuating some suitable conventional phase shifting circuit elements. This results in shifting of the regions where the energy is directed.

The use of two mirrors with their cooperating oscillators as above described offers certain advantages. In the first place the radiations are focused at *f*, thus increasing the energy input to the region. Furthermore, each oscillator may send energy in the focal region *f* regardless of its phase relation or frequencies. However, there is an advantage in having both oscillators at the same frequency and therefore a constant phase relation, since unconsumed energy from one oscillator can go over to the other, be taken up by it and then returned to *f*. It will be apparent, however, that apparatus with two mirrors with their cooperating oscillators would fall within the scope of the present invention. The mirrors could be disposed radially from their common focal region *f*.

In certain cases, in breaking down air to activate the nitrogen for use in preparing nitrates, for example, it may be advantageous to use incident means for the initial breakdown of the region *f*. But when the free flame is once established, the energy can be fed into it by ignition in accordance with the present invention and the process continued with electrical energies that are lower than those required to break down the medium. Whenever the expression "a plurality" is used in the specification and claims, it is to be understood as meaning "two or more."

7 suitable sparking electrodes connected to a source of sparking potential may be used for initial breakdown. Such a device is diagrammatically shown, comprising two sparking electrodes 46 and a source of sparking potential 48. It is to be understood that the present invention can be embodied in other specific forms without departing from the spirit or essential attributes thereof, therefore desire the present description to be considered in all respects as illustrative and not restrictive, reference being had to the appended claims rather than to the foregoing description to indicate the scope of the invention.

What is claimed is:

Apparatus for treating gaseous media com-

prising: a source of short wave electrical energy; a radiator coupled to said source of energy, a focusing device for concentrating the energy emanating from said radiator into a confined region of space adapted to receive the gaseous medium to be treated; and a phase-shifting device connected between said source of energy and said radiator for altering the instantaneous phase of said energy, whereby the instantaneous position of the maximum intensity of said energy within the medium-treating region may be shifted.

2. Apparatus for treating gaseous media comprising: a source of short wave electrical energy; a radiator coupled to said source of energy; a focusing device for concentrating the energy emanating from said radiator into a confined region of space adapted to receive the gaseous medium to be treated; and a conduit extending into the medium-treating region for collecting the products of the treatment.

3. Apparatus for treating gaseous media comprising: a source of short wave electrical energy; a radiator coupled to said source of energy; a focusing device for concentrating the energy emanating from said radiator into a confined region of space adapted to receive the gaseous medium to be treated; said focusing device including an enclosure containing a medium of higher insulating value than that of the medium-treating region; and a conduit extending into said medium-treating region for collecting the products of the treatment.

4. Apparatus for treating gaseous media comprising: a plurality of opposed sources of short wave electrical energy of like frequency; a radiator coupled to each of said sources of electrical energy; opposed focusing devices for concentrating the energy emanating from said radiators into a common, confined region of space adapted to receive the gaseous medium to be treated; and a phase-shifting device connected between each of said sources of energy and the radiator coupled thereto; said phase-shifting devices being adjustable for altering the instantaneous relative phases of said sources of energy, whereby the instantaneous position of the maximum intensity of the resultant energy within the common medium-treating region may be shifted.
